UNITED STATES PATENT OFFICE.

JOHN H. GUEST, OF BROOKLYN, NEW YORK.

ELECTRIC-ARC LAMP.

SPECIFICATION forming part of Letters Patent No. 279,152, dated June 12, 1883.

Application filed September 8, 1882. (No model.)

To all whom it may concern:

Be it known that I, JOHN H. GUEST, of Brooklyn, in the county of Kings and State of New York, have invented an Improvement 5 in Electric-Arc Lamps, of which the following is a specification.

I make use of a solenoid-magnet in a shunt between the + and — binding-posts to draw one carbon toward the other, against the action of a spring, and I employ a peculiar arrangement of pawls whereby the carbon-holder and rack is lowered and fed one or more notches at a time, as more fully set forth hereinafter.

15 In the drawings, Figure 1 is an elevation, partially in section, of the feeding mechanism. Fig. 2 is a sectional plan below the line $x-x$. Fig. 3 is a diagram illustrative of the circuit-connections. Fig. 4 is a rear view; Fig. 5, a 20 side view of the dash-pot and its mechanism. Fig. 6 is a sectional plan, in larger size, of the dash-pot pawl and pulley. Fig. 7 is an elevation, partially in section, of the pawl mechanism and dash-pot as applied with two reac- 25 tory solenoids in the shunt. Fig. 8 is a side view of the mechanism shown in Fig. 7, and Fig. 9 is a sectional view of the magnet for drawing down the lower carbon and locking the same.

30 a and a' are the plates connected by the standards. b and b' is a movable case surrounding the mechanism. d is the rack-bar; $d' d''$, the upper-carbon holder and carbon; and d'' is the lower carbon and its holder d^4 .

35 If the lamps are to be burned in multiple arc, it will not be necessary to apply a lower magnet to draw down the lower carbon and establish the arc, because the carbons in that case are placed in the lamps so as not to touch each other; but when the lamps are burned in 40 series, the carbons will be placed in the lamps so as to touch each other, and a magnet is to be employed to separate the carbons by drawing down the lower carbon, as hereinafter de- 45 scribed.

In Fig. 3 the circuit-connections are shown from the binding-post + through $a a' d d' d'' d^4$ to the plate d^5 , thence by the insulated column d^6 and wire to the insulated — binding-post. The solenoid-helices f are in a shunt between + and — binding-posts. The cores e of

the solenoid f are joined by a cross-bar, e' , to which there is a rod, e^2 , attached, that is guided at the lower end by the bracket 2 from the column b , and at its upper end the rod e^2 passes 55 through and is guided by the top plate, a . There is a helical spring, h , around the rod e^2 , resting at the bottom on the bracket 2, and acting at its upper end against the adjusting-nut 3 to lift the rod e^2 , cross-bar e' , and cores e , to- 60 gether with the parts connected with such cross- bar e' . It is to be borne in mind that this spring h acts in the opposite direction to the solenoid; hence when the current passing through the helix of the solenoid increases, in consequence 65 of resistance in the main circuit through the carbons, the cores and cross-bar will be drawn down, and when the resistance between the carbons lessens, the spring h raises the cores and cross-bar in consequence of the diminished 70 energy of solenoid in the shunt.

The rod or rack-bar d of the carbon-holder is made with teeth at its two edges, and also at the back, said rod being T-shaped, as seen in Fig. 2. The teeth at the two opposite edges are 75 acted upon by pawls that are controlled by the cross-bar e' , and the back teeth are used in connection with a dash-pot to prevent the carbons feeding too fast, and, as hereinafter de- 80 scribed, as the pawls that support the carbon- holding rack are withdrawn from the carbon- holder by the action of the solenoid f , the pawl that intervenes between the back row of teeth and the dash-pot is brought into action, to prevent the carbon-holding rack dropping 85 too rapidly when the feeding-pawls are disengaged.

The two pawls i are provided with arbors or cross-shafts 4, (see Fig. 2,) that are pivoted in the hanging stationary frame-pieces i^2 , the lower ends of which are formed as jaws for the reception of the arbors or shafts 4. These pawls are somewhat triangular in shape. The teeth or ends that engage with the teeth 5 on the edges of the rack d are slightly below the 95 shafts 4, and there are links o connected at their outer ends by screws 6 to the pawls i , and at their inner ends they come together and are connected by a wire, 7, that forms a hinge-pin to the links, and is itself rigidly attached to 100 the cross-bar e' of the solenoid; hence it will be seen that as the cross-bar and solenoid-cores

rise and fall, the links *o* swing the pawls *i* on their fixed arbors *4*, and the ends of the pawls in contact with *5* describe arcs of circles. In the downward movement the points of the 5 pawls draw away from below the teeth *5* and lower the carbon-holding rack and carbon. In their upward movement these pawls raise the carbon-holder, and the downward movement takes place as aforesaid, when the current 10 through the shunt increases, and hence the distance between the carbons is lessened and the equilibrium restored.

The carbon and rack are lifted by the spring *h*, acting through the pawls, when the carbons 15 are too near together. The lowering of the carbon and rack continues as the carbons are consumed, and finally the pawls *i* draw so far back as to disengage from the teeth *5*, and the carbon-holder rod and upper carbon would 20 then drop until again caught by the pawls acting on the next pair of teeth above, as the power of the solenoid *f* lessens, and the spring raises the cores and pawls; but to prevent this 25 movement being sudden and affecting the light, and to sustain the carbon and lower it gradually, I employ the means next described.

There is a small cylinder, *k*, in which is a heavy piston, (shown by dotted lines,) and to the piston is the rod *l*, that is connected at its 30 upper end by a cord, *l'*, to the segmental pulley *n*. This pulley *n* is upon an axis, *9*, in the swinging frame *m*, that is hung at its upper end by a pivot in the stationary jaw *n'* below the plate *a*. By withdrawing the pins 35 from the jaw *n'*, the pivot and swinging frame *m* can be lifted off for cleaning or adjustment.

The weight of the piston in *k* tends to turn the segmental pulley *n* until its stop comes in contact with the screw *11*, that passes through 40 an arm extending out from the frame *m*.

There is a pawl, *p*, that is pivoted by the axis of the segmental pulley *n* and rests within the opening in said segmental pulley, and in the normal position said pawl is slightly inclined 45 upwardly, as seen in Fig. 8. The end of the pawl *p* is not engaged with the teeth *6* of *d* in the normal position; but it is brought into engagement by the movement of the parts next described before the pawls *i* separate from the 50 teeth *5*, so as to cause the pawl *p* to partially support the carbon-holder and carbon.

At the bottom end of the hanging frame *m* there is a cross-bar, *s*, and there are two bent levers, *rr*, pivoted at 55 in fixed standards *16*. The short ends of these bent levers are behind the cross-bar *s*, and the longer ends are behind the lower ends of the pawls *i*, so that as these 60 pawls *i* swing downwardly and outwardly, the frame *m* is moved toward the teeth *6* until the pawl *p* engages with said teeth, which takes place before the pawls *i* drop the teeth of *5*; hence the weight of the carbon-holder and carbon is suspended by the pawl *p*, and descends gradually as the weighted piston is drawn up 65 in the dash-pot against the pressure of the confined air. The stop 17 on the segmental pul-

ley and the screw *11* allow the parts to be adjusted so that the pawl *p* will be in the proper position to engage one of the teeth *6* as the frame *m* is swung toward the rack, as aforesaid. 70 The resistance at the arc lessening by the carbons approaching, the solenoid-magnet in the shunt weakens, and the cross-bar and pawls are instantly lifted by the spring *h*, and the pawls take the next teeth and support the carbon and rack, and the operations are repeated. 75

I make use of the stop-screw *20*, passing through a bracket on *a*, and acting at the upper end of the rod *e'*, to limit the upward movement of the solenoid, to prevent the carbons being separated too far. As the solenoid-cores are drawn downwardly into the helices the electric energy becomes less efficient in moving said cores; hence the variation in the resistance at the arc between the carbons has to 85 be considerable. To compensate for this I use the adjustable magnet-cores *t t* upon a cross-bar, *r*, through which passes the adjusting-screw *r'*. These cores *t* become magnetized and attract the cores *e*, and that attraction increases the nearer the cores *e* come to the cores *t*, and by the adjustment of the cores *t* the parts can be placed in such a position that the carbon will be raised or lowered by a very slight variation in the strength of current passing 90 through the shunt. A similar effect will be produced by the use of a second solenoid-magnet, *u*, in the shunt-circuit. (See Figs. 7 and 8.) The cores *u'* of this magnet *u* are upon a cross-bar, *u'*, fastened to the vertical rod *e'*. These 100 cores *u'* pass but a short distance into the helices *u*, and they are hence operative in moving the vertical rod *e'* and pawls *i* when the longer cores *e* of the magnet *f* are not as powerfully acted upon in consequence of having moved 105 into the solenoid-helices. The solenoid-magnet *u*, (shown in Figs. 7 and 8,) serving to equalize the action of the parts in place of the adjustable cores *t*, Fig. 1, does not require to be as powerful as the solenoid *f*; hence the wire is 110 represented as coarser in the helix of *u*. In this case the cores *u'* tend to continue the feeding movement as the action of the cores *e* weakens; and hence these cores *u'* are the equivalents of the cores *t*, which latter, by their attraction on the cores *e*, effect the same object. In both instances the helices that act on these 115 cores *u'* and *t* are in the shunt-circuit.

I find it advantageous to lessen the resistance in the lamp-circuit after the carbons have been 120 drawn apart, because by so doing the flow of current is not so much obstructed.

The electro-magnet *u'*, that acts upon the armature *u* of the lower-carbon holder *d'*, is of any desired character. It may be made 125 with four helices, as in my Patent No. 259,007, and the current passes from the carbon holder or frame through the helix of such magnets *u'*, and by the wire 23 to the frame or column *d'*, thence to the negative post. 130

I make use of a spring-latch, *e'*, to hold down the lower-carbon holder. This latch is shown

as a sliding bar placed transversely of the carbon-holder through slots in the tubes that guides such carbon-holder. There is a spring, e^8 , that moves the latch endwise after the lower 5 carbon has been brought down by the magnet, and the shoulder at 24 prevents the carbon-holder rising until the latch e^1 is pushed back by hand. The end of the latch short-circuits the current past the magnet u^4 by connecting 10 the carbon-holder d^4 to the insulated stud e^9 , from which is the wire 23, leading to the negative binding-post.

I claim as my invention—

1. The combination, with the carbon-holding 15 rack and circuit-connections passing through the carbons, of a solenoid helix in a shunt-circuit between the + and — binding-posts, the cores and cross-bar of such solenoid, a spring 20 acting in the opposite direction to the solenoid-magnet teeth on the carbon-holding rod, pawls to support the same, links between the pawls and the cross-bar of the solenoid-cores, substantially as set forth, whereby the pawls are 25 swung downwardly to feed the carbon by the action of the solenoid, or raised to separate the carbons by the action of the spring, substantially as set forth.

2. In an electric lamp, the combination, with the carbon-holding rod with ratchet-teeth, of 30 swinging pawls to lower the carbon-holder, a dash-pot, a pawl, and connections, substantially as set forth, whereby the carbon-holder is partially supported by the dash-pot and its

pawl while the main pawls let go one set of teeth and grasp the next in feeding the carbon, 35 substantially as specified.

3. The combination of the solenoid-cores e , cross-bar e' , spring h , pawls i , links o , and carbon-holder rod, and the hanging frame m , segmental pulley n , pawl p , dash-pot, levers r , 40 and connections, substantially as set forth.

4. In an electric lamp, the combination, with the carbons and carbon-holders, of a magnet in the main circuit to establish the arc, mechanism for supporting the upper carbon and allowing it to be fed, a solenoid-magnet in a shunt between the + and — binding-posts, with a core 45 acting to feed the carbon, and a second solenoid-core acted upon by the helix in the shunt, for equalizing the action of the parts in feeding the carbon, substantially as specified.

5. The combination, in an arc-lamp, of a lower-carbon holder, an electro-magnet and armature to draw down such carbon-holder, a latch to hold the parts, and circuit-connections, substantially as set forth, for short-circuiting the current around the electro-magnet by the movement of the latch, substantially 55 as set forth.

Signed by me this 6th day of September, A. 60
D. 1882.

J. H. GUEST.
